US00D901008S

(12) **United States Design Patent** (10) Patent No.: **US D901,008 S**
(45) Date of Patent: ** Nov. 3, 2020

(54) **CAP OF AN INJECTION DEVICE**

(71) Applicant: **Sanofi-Aventis Deutschland GMBH**,
Frankfurt am Main (DE)

(72) Inventors: **Courtney Nicholas**, East Greenbush,
NY (US); **Scott Barton**, East
Greenbush, NY (US); **Bart Burgess**,
East Greenbush, NY (US); **Alexei**
Goraltchouk, Cambridge, MA (US);
Alex Zuyev, Frankfurt am Main (DE)

(73) Assignee: **Sanofi-Aventis Deutschland GMBH**,
Frankfurt am Main (DE)

(**) Term: **15 Years**

(21) Appl. No.: **29/645,284**

(22) Filed: **Apr. 25, 2018**

(30) **Foreign Application Priority Data**

Oct. 25, 2017 (EM) 004420388

(51) LOC (12) Cl. **24-02**

(57) **CLAIM**

The ornamental design for a cap of an injection device, substantially as shown and described.

DESCRIPTION

FIG. 1 is a perspective view of a cap of an injection device showing our new design;

FIG. 2 is a second perspective view thereof;

FIG. 3 is a front elevation view thereof;

FIG. 4 is a rear elevation view thereof;

FIG. 5 is a side elevation view thereof;

FIG. 6 is a top plan view thereof; and

FIG. 7 is a bottom plan view thereof.

FIG. 8 is a first perspective view thereof;

FIG. 9 is a second perspective view thereof;

FIG. 10 is a front view thereof;

FIG. 11 is a back view thereof;

FIG. 12 is a side view thereof;

FIG. 13 is a top view thereof; and,

FIG. 14 is a bottom view thereof.

The broken lines show portions of the design that form no part of the claimed design.

1 Claim, 8 Drawing Sheets
